[57] **CLAIM**

The ornamental design for an overhead projector, as
shown and described.

DESCRIPTION

FIG. 1 is a front, top, and right side perspective view of
an overhead projector showing our new design;

FIG. 2 is a top plan view thereof;

FIG. 3 is a front elevational view thereof;

FIG. 4 is a rear elevational view thereof;

FIG. 5 is a right side elevational view thereof; and

FIG. 6 is a left side elevational view thereof.

The undisclosed bottom is plain and unornamented.
